ELECTRIC STARTER

Albert Callsen and Anton Schmid, Stuttgart,
Germany, assignors to Robert Bosch Aktien-
gesellschaft, Stuttgart, Germany

Application March 17, 1934, Serial No. 716,054
In Germany April 25, 1933

2 Claims. (Cl. 74—7)

This invention relates to electric starters for internal combustion engines of the type wherein a friction ring attached to the engine flywheel is adapted to be gripped in driving engagement between a pressure shell adjustable on the starter shaft and an opposite disk also mounted on the shaft.

In the previous constructions of this type it has been proposed to position the pressure shell and its adjusting mechanism on the side of the friction ring away from the starter; that is, upon the free end of the starter shaft. A number of disadvantages arise from such a construction, it being found that under certain circumstances the gripping mechanism is not quickly released from the friction ring when the engine starts. Also the diameter of the pressure shell and the parts rotating therewith is limited by the engine flywheel lying in the same plane, wherefore the inertia of the shell is too small and starting of the friction gearing more difficult. Furthermore, a large part of the turning moment upon starting the engine must be carried by the free portion of the starting shaft projecting beyond the bearing of the starting motor. Under great loads this may result in bending of the shaft and jamming of the gearing.

It is the principal object of this invention to eliminate these disadvantages. To this end it is a feature of the present invention to journal the pressure shell in the starter bearing whereby only the opposite disk and the part of the pressure shell coming into contact with the friction ring lie beyond the bearing.

Other objects will in part be obvious and in part be pointed out hereinafter.

To the attaining of the aforesaid objects and ends the invention still further resides in the novel details of the construction, combination and arrangement of parts all of which will first be fully described in the following detailed description and then be particularly pointed out in the appended claims, reference being made to accompanying drawing which represents a longitudinal section with parts shown in side elevation of the flywheel end of a starting motor constructed in accordance with the present invention.

In the embodiment shown in the drawing *a* indicates the armature in the electric starting motor and *b* the armature shaft. Sleeve *c*, which forms the pressure shell, is rotatable on the shaft *b* and is also slidably journaled in the bearing *d* of the starter so that the armature shaft is journaled in bearing *d* by means of the shell. A disk

e is axially rotatable on the shell but held against rotation relative thereto by means of key *f*. Arranged between this disk and the shell are a plurality of strong spring disks or washers *g*. On the side away from the shell the disk *e* is provided with a cam track *h* on which run the rollers *i*. The rollers are carried in a holder *k* wedged onto the armature shaft. In order to save space the holder is positioned under the winding heads *m* of the motor armature *a*. A ring *n* is keyed on the end of the armature shaft *b* and held fast by nut *o*. This ring *n* provides the opposing disk of the friction gearing between the facing surfaces of which lies the friction ring *p* of the flywheel of an internal combustion engine.

The advantages of the invention consist in the fact that the starting motor shaft is journaled between those places at which the starting moment of the shaft is carried over to the pressure shell and the opposing disk *n* so that the free carrying length of the armature shaft is short from the journal to the point of power application.

The construction is further advantageous in that the shell with its actuating mechanism is substantially contained within the motor housing whereby the same is fully protected and considerable space saved. It is also advantageous in that it is not necessary to limit the diameter of the torque disk *e* as would be necessary if the same were placed on the outer end of the armature shaft *b* where a large diameter would not be permitted because of its proximity to the engine flywheel. This permits sufficient swing to be given to assure connecting in of the friction gear. The large diameter of the disk also permits the use of plates or disks *g* for springs which may be easily set for any desired spring pressure and make it possible to obtain great spring pressure in small space.

The above described construction also permits a better arrangement when installed, which will be appreciated when it is remembered that in many vehicles the space around the flywheel is very limited and therefore the construction of the starter must remain as small as possible. The reduction in the size of the part extending beyond the housing of this starter is therefore a decided advantage.

Having thus described the invention what is claimed as new is:

1. In an electric starter for internal combustion engines, a friction ring mounted on the flywheel of the engine, a starter shaft, a disk mounted thereon adjacent one side of said friction ring,

a pressure shell journaled in a bearing of said shaft on the opposite side of said friction ring and adjustable longitudinally of the starter shaft, cam gearing for adjusting said shell, said gearing including a cam disk mounted for rotation with and adjustable longitudinally on said pressure shell, and a plurality of plate springs between said cam disk and shell.

5. 2. In an electric starter for internal combustion engines, a friction ring mounted on the flywheel of the engine, a starter shaft, a disk thereon

adjacent one side of said friction ring, a pressure shell surrounding said shaft and journaled in a bearing thereof on the opposite side of said friction ring and adjustable longitudinally of the starter shaft, and cam gearing including a cam 5 disk having a high inertia adjustable but not rotatable on said pressure shell for adjusting the same, said cam gearing being arranged in the starter.

ALBERT CALLSEN. 10
ANTON SCHMID.
